UNITED STATES PATENT OFFICE.

DUGALD H. ROBERTS, OF DETROIT, MICHIGAN.

DESIGN FOR A LUBRICATOR-BODY.

SPECIFICATION forming part of Design No. 35,104, dated September 17, 1901.

Application filed August 12, 1901. Serial No. 71,857. Term of patent 14 years.

To all whom it may concern:

Be it known that I, DUGALD H. ROBERTS, a citizen of the United States, residing at Detroit, in the county of Wayne, State of Michigan, have invented and produced a new and original Design for a Lubricator - Body, of which the following is a specification, reference being had to the accompanying drawings, and to the figures of reference marked thereon, which form a part of this specification.

This invention relates to a design for a lubricator-body; and it consists in the formation illustrated in the accompanying drawings, in which—

Figure 1 is a perspective view of my design. Fig. 2 is a plan view thereof.

The leading feature of my design consists in a cylindrical body portion surmounted by an oblong globular portion extending centrally from one end thereof and having a central aperture at the top.

Referring to the characters of reference, 1 designates the cylindrical body portion, from which depends an annular boss 2. Projecting centrally from one end of the cylindrical body is the oblong globular portion 3, having a reduced upper end 4, in which is a central aperture 5, the whole presenting an ornate and harmonious figure.

Having thus fully set forth my invention, what I claim as new, and desire to secure by Letters Patent, is—

The design for a lubricator-body substantially as herein shown and described. 35

In testimony whereof I sign this specification in the presence of two witnesses.

DUGALD H. ROBERTS.

Witnesses:

E. S. WHEELER,
C. E. JOSLIN.
